CLAIM

The ornamental design for an attachable sweat guard with perforated removable end, as shown and described.

DESCRIPTION

FIG. 1 is a perspective view of an attachable sweat guard with a perforated removable end;

FIG. 2 is a front view thereof with a rear view being a mirror image;

FIG. 3 is a left side view thereof with a right side view being a mirror image;

FIG. 4 is a top view thereof; and,

FIG. 5 is a bottom view thereof.

The curved line drawn in broken lines in FIGS. 1 and 4 represents perforations. The lined surface pattern partially shown in FIGS. 1 and 4 represents an overall pattern within the designated area.
